UNITED STATES PATENT OFFICE.

BURNHAM C. STICKNEY, OF RUTHERFORD, NEW JERSEY, ASSIGNOR TO UNDERWOOD TYPEWRITER COMPANY, OF NEW YORK, N. Y., A CORPORATION OF DELAWARE.

TYPEWRITING MACHINE.

Application filed October 23, 1924. Serial No. 745,281.

This invention relates to typewriting machines which employ work-webs made up of printed forms; carbon-sheets being interleaved with the web-plies, and relative shifting of the carbons being effected from form to form as the typing proceeds.

One of the main objects of the invention is to simplify and improve the construction and operation of this class of manifolding typewriters. Usually the cylindrical platen of the typewriter has to be elevated as a preliminary to straightening out the webs, so as to render the shifting of the carbons possible; and it is one of the objects of the invention to avoid this displacement of the platen, and to avoid the necessity of complicating the platen mechanism, and to simplify the carbon-shifting operation.

Another object is to avoid the necessity of making alterations in the typewriting machine, and to construct the web and carbon handling devices so that they are in the nature of attachments, which can be connected to any standard typewriter, thus making it unnecessary to manufacture the typewriting machine with the web-handling device as a unit. The web-handling device can be manufactured and supplied separately, and can be readily applied to either new or old machines, greatly reducing the cost to the typewriter purchaser, and rendering it unnecessary as heretofore to carry in stock combined typewriting machine and web-handling units.

In carrying out the present invention in its preferred form, there hangs at the back of the typewriting machine a loop of work-web with interleaved loops of carbon, the composite loop being held stationary at its rear end, and being of such length that it permits the usual range of movement of the platen carriage, the loop swinging as its forward end is carried to the right and left by the carriage. This composite loop, moreover, is of sufficient length to permit the front end thereof to be fed line by line around the platen until a form is typed; and even at this time there is still sufficient length of loop left hanging, to permit the necessary endwise travel of the carriage.

The form having been typed, the usual feed-rolls are cast off from the platen, to release the web and carbons, and the rear

end of the composite loop is moved back, to straighten out the loop, and also to pull the typed web back around the platen, this retraction proceeding until the forward ends of the carbons are withdrawn from the typewriting machine, and the carbons themselves lie in flat condition from end to end, the work-web plies being also flattened. At this time the feed-rolls may be again thrown onto the platen, and the platen may be revolved to pull forwardly the plies of work-web while the carbons remain stationary, the same being held back by their rear ends. At this time the web plies are pulled forwardly to the extent of one form, thereby bringing the first untyped form into facewise relation with the front ends or portions of the carbons. Then the looping frame or device is moved forwardly to recreate the loop, which again dangles at the rear of the typewriting machine. Then the platen is rotated to bring the first untyped form into the typewriter and around the platen, together with the forward ends of the carbons; whereupon typing of such form proceeds. Suitable leading-end work-gages are provided for the various steps, and a knife is also provided for severing the web.

One of the advantages of the invention arises from the simplicity of operation, the work-web plies always remaining in position around the platen and conveniently operated thereby. If preferred, the work may be pulled around the stationary platen by hand and set up to the gages. The gages may mechanically determine the length of shift of the web relatively to the carbons, and also the length of form to tear off.

Other features and advantages will hereinafter appear.

In the accompanying drawings,

Figure 1 is a sectional diagrammatic side elevation, showing the platen and the paper-tables, and showing the shifting forward of the work-plies as having been completed relatively to the stationary carbons, while the latter are being held stationary and in flat condition.

Figure 2 is a sectional diagram of an Underwood Standard typewriting machine with the present invention applied thereto, and showing the loop of web having been re-created after the completion of the web-

shifting operation seen at Figure 1. The invention may also be applied to other makes of typing machines.

Figure 3 is a similar view, showing the completion of the next step, which consists in the advance of the forward portion of the composite loop, including both the work-plies and the carbons, to bring the next un-typed form on the web (together with the interleaved carbons) into position for typing the first line of such form; and at this time these parts are in position for severing from the web the typed form, at the head of the web, but permitting the form that has last been typed to remain unsevered from the web.

Figure 4 is an elevation of the typewriting machine and the web-handling devices attached thereto, showing the step which is taken after the completion of the typing of a form, namely, the straightening out of a composite web preparatory to advancing the web-plies alone to the position seen at Figure 1 while the carbons remain stationary.

Figure 5 is a front elevation of the platen and platen-frame, showing the adjustable web-severing knife supported on brackets attached to the ends of the platen-frame, and also showing a table or work-web support carried on the same brackets and provided with gages for the leading edge of the web.

Figure 6 is a plan of the Underwood Standard typewriting machine with the web-handling attachments fixed thereto, and showing the composite web in straightened-out condition preparatory to effecting a relative shift between the work-web and the carbons, as at Figure 4.

The standard Underwood typewriting machine comprises a revoluble platen 10, journaled in a platen-frame 11, the latter supported upon a letter-feeding carriage 12, running upon rear and front rails 13, 14; key-operated type-bars 15 striking against the front of the platen.

The platen-frame comprises a rear introductory paper-shelf 16, extending forwardly and down to the platen. A stationary front paper-guide 17 is mounted upon the typewriter frame. Upon the bottom of the platen run pressure rolls 20, which may be cast off to release the work; but which co-operate with the platen at the operation of line-feeding the paper, and also when rapidly advancing or retracting the paper; the platen being revoluble by either the line-spacing mechanism 21 or the platen knobs 22.

The work-web comprises a number of plies 23, which may be drawn from any source of supply (not shown) at the rear of the typewriter stand 24. These plies may be loose and separate, or they may be joined in the form of a fan-folded web. On entering the typewriting machine, the work runs down upon the rear paper-shelf 16, and forwardly

around the under side of the platen and up in front thereof, and is delivered along a table or support 25 mounted at the delivery side of the platen, the work being carried around the platen by the rolls 20 at the line-feeding operation. As seen at Figure 3, the work-plies are interleaved with carbon-sheets 26, so that all the work-plies are typed.

During the letter-feeding operations of the carriage, the composite web, i. e., the work-plies with the interleaved carbons, is fesooned or hangs in a slack or loop 27 in rear of the Underwood typewriting machine 28, the forward end of the loop being caught by the feed-rolls 20 and platen 10, and hanging from the top edge of the rear paper-table 16. This end of the loop swings or travels edgewise with the paper-carriage at the letter-feeding movements. At its rear end, however, the loop is stationary during the typing operation, the rear ends of the carbons being secured to carbon-blades 29 of a form known in this art, said blades being stationary during all the typing and line-feeding operations. The plies of work-web 90 hang from a rounded shelf or bar 30, which is also stationary during the typing operations. The work-plies hang from said bar down behind the typewriter stand 24, whence they extend to the usual web receptacle or other source of supply. The composite loop 27 is of such ample length that the forward ends of the carbons may feed up around the platen from the Figure 3 position (which shows the carbons in position for typing the first line on the fresh form) far enough to type the entire form, while still leaving the loop 27 of sufficient length to accommodate the endwise travel of the carriage between its extreme positions for writing a full length line upon the web. The remainder of the loop or slack in the web, at the completion of the typing of a form thereon, is indicated by the dotted line 32 in Figure 2; the length of this remainder being dependent upon the length of the printed forms into which the work-web is originally divided.

At the completion of the typing of a form, there must be relative shift between the carbon-sheets and the work-plies, sufficient to bring the carbon-sheets face to face with the next printed form on the web-plies preparatory to typing the same. This invention not only provides for the looping of the composite web both to give a supply for the line-feeding operations and also to allow for the travel of the carriage, but also provides a simple method for effecting such relative carbon-shift, and of overcoming the difficulty of effecting a shift through a looped composite web; and the further advantage is gained of effecting a shift while the work-plies remain in position around the platen, thus conduceing to simplicity of construction and operation.

Preparatory to effecting the carbon-shift, the loop 27 is brought into substantially straight condition. For this purpose the holders 29, and the carbon-carrier or block 33 upon which they are fixed and through which the work-plies 23 are threaded, are all-mounted upon the free ends of arms or frame 34, which are pivoted at 35 to swing backwardly from the position at Figure 2 (where the composite web is held in typing condition) to the flattened-out condition seen at 36, Figure 4. The flattening or straightening of the webs is important, it being known in this art that it is difficult or impossible to advance a multiplicity of carbons between stationary work-sheets around a platen, or through any other undulatory or tortuous path, but that they can be slipped readily past the work-sheets (or vice versa) if the sheets and carbons are flattened or substantially straight. The carbon-carrier 33 is preferably so mounted upon the arms 34 that it assumes a level position at this time, to agree with the level condition of the composite web, as at Figure 4. The arms 34 are held rigidly at their upper ends by a cross-bar 37, and at their lower ends by a rock-shaft 35, so as to form a rigid rectangular frame swingable between the positions at Figures 2 and 4; said rock-shaft 35 being journaled in the rear ends of angle-plate bracket-arms 38, which extend rearwardly from beneath the base of the typewriter 28 and are rigidly connected at their rear ends by a stiffening cross-bar 39 riveted thereto. These fixed arms 38 are attached to the typewriting machine without alteration in said machine, being held up against the bottom of said machine by screws 40, which are usually provided for holding on the four rubber feet 41 of the typewriter; the arms having perforations up through which the screws 40 pass as they are threaded up into the perforated holes usually provided in the Underwood typewriter for them. The usual screws thus hold the rubber feet and the arms 38 rigidly upon the machine.

For giving the frame 34 its motion from the looping position at Figure 2 to the web-straightening position at Figure 4, there is preferably employed a handle 42, of any suitable form and location, which is shown in this instance as mounted upon an upstanding lever 43 placed at one side of the typewriting machine and pivoted at 44 upon one of the attached bracket-arms 38; said lever being part of a bell-crank, the lower arm of which is indicated at 45. Said arm 45 is pivoted at 46 to the forward end of a link 47, the rear end of which is pivoted at 48 to one of the arms 34 of the web-straightening frame. During the typing operations the handle 42 remains in the idle position at Figure 2; but preparatory to the

paper-shifting operation said arm 43 is swung up to the position at Figure 4, thereby swinging down the arm 45 and driving the guiding link 47 backwardly, whereby the frame 34 is swung to its extreme rear position, in which position it may be locked by the toggle action of the parts 45, 47; a stop 49 fixed on a bracket-arm 38 limiting the downward movement of arm 45, so that the frame 34 is locked against vibrating either upwardly or downwardly at this time.

Preparatory to swinging the frame 34 back from the typing position at Figure 2, the releasable feed-rolls 20 are cast off from the platen by the key (not shown) usual on the Underwood typewriter, and this release of the composite web is effected so that the backward movement of the frame 34 may be permitted to continue past the point at which it straightens out the remainder 32 of the original loop. During this supplemental rearward movement, the composite web is pulled back around the platen, and the form which has just been typed is pulled clear of the typewriting machine, the leading ends of the carbons being now located at a point back of the paper-shelf 16, thus permitting the carbons to extend in substantially flat condition from their forward ends to their rear ends, as at Figure 4.

At this time there is a leading portion of the composite work-plies still extending around the platen, as at 50, Figure 4, this leading portion consisting of the work-form which next precedes the form that has just been typed. Usually therefore there are two typed work-forms in the machine; the unsevered previously typed head form 50 being retained to serve as a means for advancing the web relatively to the carbons.

The feed-rolls 20 having been restored, the platen is rotated, and by co-operation with said rolls pulls forward the web-plies over the top of the paper-shelf 16 and between the carbon-holding blades 29, and over the rounded transverse apron or bar 30 and up from the source of supply; while the carbons are held stationary by the fixed blades 29, said carbons, because of their flat and unbound condition, offering no appreciable obstruction to such advance of the work-plies. This relative work-shifting is continued until the leading end of the web, i. e., the top edge of the previously typed form 50, reaches a gage 51, as at Figure 1, this marking the completion of the relative work-shift and bringing the first untyped form on the web over the leading end portion of the set of carbons. It will be noted that at this time the two typed forms, one after the other, reach from the top edge of the paper-shelf 16 down around the platen and up to the gage 51. The leading typed form on the web has no further function to

perform. The second typed form serves in the subsequent step of the web-handling operation.

The parts being now in the position seen at Figure 1, the handle 42 is pulled forwardly to the position at Figure 2, against a stop 53 which is also provided upon a bracket-arm 38. This moves forward the web-controlling frame 34 to the position for typing at Figure 2, and recreates or forms a fresh loop or slack 27. The weight of 34 holds it in forward position. By further use of the platen-knob 22, the platen may be revolved, and by co-operation with the feed-rolls 20 it may draw forward the composite web from the position at Figure 2, carrying the carbons (together with the first untyped form on the webs) forwardly under and up around the platen to the position seen at Figure 3, preparatory to typing the new form. The extent of this advance may be mechanically determined by a gage 54. At this time the loop 27 is partly taken up, as at 54^a, Figure 2. When the leading edge of the web is brought up against gage 54, the first work-form may be torn off by means of a severing knife 55, which may be provided at the delivery side of the platen. This leaves one typed form extending from the knife down nearly to the printing line on the platen, to serve in manipulating the web at the next carbon-shift operation. It will be understood that when originally introducing the web into the machine, the first form may be left untyped if desired, and may extend from the platen over the rear paper-shelf 16, as at Figure 4; this single untyped form being subsequently torn off as waste.

Said gages 51 and 54 may be independently adjustable up and down a staff or work-support 56, which is fixed at its lower end upon a cross-bracket 57, the latter extending from one platen-frame end 58 to the other, said cross-bracket or frame at its ends being riveted to ears 59 formed upon bracket-plates 60 secured to the platen-frame ends 58 by the screws 61 which are usually provided upon the Underwood machine for removably securing cover plates upon said ends 58. From said brackets 60 extend upwardly arms 62, which, by means of screws 63, carry the transverse web-severing knife 55; said screws being settable into any desired holes 64 of said arms 62 for adjusting the knife to any required position for different lengths of forms. Each of the gages 51 and 54 may comprise a clip 65, whereby it is held upon the staff 56, holding the gage against accidental motion while permitting it to be adjusted along the staff.

It will be seen that all of the web-gaging and web-severing members may constitute a unit which is attachable to the platen-frame by the screws 61 usually inserted in said frame in said Underwood machine, and that

no alteration of the platen-frame is necessary or any displacement of the platen for the purpose of straightening out the composite web.

The web may be guided laterally by means of side gages 66 adjustable along a transverse rod 67 and secured by thumbscrews 68, said rod extending between the arms 34 and rigidly connecting them. The gages 66 are adjustable for different widths of web or for different widthwise positions thereof. At the typewriter carriage the webs may be guided laterally by adjustable side-edge guides 69, which are usually attached to a bead or rolled brim 70 formed upon the upper edge of the paper-shelf 16 in said Underwood typewriter; said guide 69 usually having a hook 71 catching around said bead. There may be also provided on each of these detachable side guides 69 a finger 72 extending inwardly and projecting over the side edge of the web to confine it against rising, and also to serve as a side gage.

It will be understood that when the web is being moved between the positions seen at Figures 2 and 4, the typewriter carriage should be in such a position that the web, when viewed in plan, as in Figure 6, will be straight throughout and its forward part not skewed relatively to its rear part. For this purpose the carriage may be located in a central position by the aid of a carriage-centering device, which may comprise a centering index 74 fixed upon the typewriter carriage 12, and a co-operative index 75 fixed upon the machine-frame by means of a screw 76, which usually fastens the front scale 77; the index 74 being held by a screw 78, which is usually provided upon the typewriter carriage for another purpose.

For severing the side edges of fan-folded webs, the ends of the carbon-blades 29 may be provided with diagonal knives 79 in a manner known in this art; the slitting of the webs being performed by these knives after the parts are in the positions seen at Figure 4, and after the rolls 20 have been restored to the platen, and while the platen is being rotated to draw forwardly the webs to the position at Figure 1.

As it is often desired to perform different kinds of work in alternation upon the machine, the web may be detached, together with the carbon-carrier 33, and another web with another set of carbons substituted. To facilitate this change, the carbon-carrier is held upon the frame 34, 37 by means of thumb-screws 80, which hold down a plate 81 upon cross-bar or plate 37; the stepped block 33 being fastened upon the top of said plate 81, one at each end, by rivets or other means, as shown. It will be seen that, by taking out the thumb-screws 80, the carbon-carrier, including parts 33, 81, may be removed, together with the carbons and

work-webs, and the webs may be drawn out from the typewriting machine and another carbon-carrier with another web may be substituted in the machine.

5 Since the rear ends of the carbon loops are secured to the stationary straightening-out frame, while the forward ends of said loops are fed around the platen, each carbon loop is long enough to give the desired 10 sidewise swing of the slack in rear of the typewriter, and to extend around the platen far enough for the typing of the last line on the work-form. Only the forward portion of the carbon loop is used. It is evident that each carbon loop may be removed 15 and turned end for end, thus bringing a fresh area of the carbon into use. If desired, the carbon loop may be manufactured with carbon on only its front portion, leaving the main portion of the loop uncarbonized, for economy.

It will be noted that the means for withdrawing the carbon loops does not entail the addition of any mechanism or weight to the 25 typewriter carriage, and the necessity of making a special carriage is avoided, while there is preserved the advantage of a side-wise swinging loop which is line-fed at its front end while stationary at its rear end; 30 the work-web remaining in engagement with the platen when the loop-supporting frame is in its extreme rearward position, so that the platen and feed-rolls may be employed if desired for the purpose of advancing the 35 work-webs independently of the carbon loops.

Variations may be resorted to within the scope of the invention, and portions of the improvements may be used without others.

40 Having thus described my invention, I claim:

1. In a typewriting machine, the combination of a rotatable platen, a letter-feeding carriage therefor, and a support at the introductory side of the platen for supporting the rear end of a composite loop of multiple-ply work-web and carbons, the front end of the loop being connected with the platen, said loop-support being stationary during 45 the travel of the carriage and being movable rearwardly of the web to straighten out the loop.

2. In a typewriting machine having a rotatable platen and a letter-feeding carriage therefor, the combination with a support or holder to which the rear ends of carbons are attached, said support mounted at the introductory side of the platen for supporting the rear end of a loop or slack 50 of multiple-ply work-web interleaved with the carbons, the front end of the loop being connected to the platen, and said loop-support being stationary during the travel of the carriage, of means to move said loop-support 55 backwardly to straighten or lengthen 60

en out the loop and pull the composite web backwardly to clear the carbons from the typewriting mechanism, while the leading portion of the work-web remains upon the platen.

3. In a typewriting machine having a rotatable platen and a letter-feeding carriage therefor, the combination with a support or holder to which the rear ends of carbons are attached, said support mounted at the introductory side of the platen for supporting the rear end of a loop or slack of multiple-ply work-web interleaved with the carbons, the front end of the loop being connected to the platen, and said loop-support being stationary during the travel of the carriage, of means to move said loop-support backwardly to straighten or lengthen out the loop and pull the composite web backwardly to clear the carbons from the typewriting mechanism, while the leading portion of the work-web remains upon the platen, and releasable means co-operating with the platen for advancing the web relatively to the carbons.

4. In a typewriting machine having a rotatable platen and a letter-feeding carriage therefor, the combination with a support or holder to which the rear ends of carbons are attached, said support mounted at the introductory side of the platen for supporting the rear end of a loop or slack of multiple-ply work-web interleaved with the carbons, the front end of the loop being connected to the platen, and said loop-support being stationary during the travel of the carriage, of means to move said loop-support backwardly to straighten or lengthen out the loop and pull the composite web backwardly to clear the carbons from the typewriting mechanism, said loop-support including a part detachable, together with the carbons and web, to permit the substitution of another carbon-holder with other carbons and web-plies.

5. In a typewriting machine, the combination with a revoluble platen, feed-rolls to run thereon, and a carriage for said platen, of a rearwardly movable frame at the introductory side of the platen, a set of carbon-blades or holders upon said frame between which plies of work-web are threaded, said frame being stationary during all the letter-feeding and line-feeding movements of the carbons and work-web, and being shiftable rearwardly to clear the carbons from the platen, and means to limit the rearward movement of said frame.

6. In a typewriting machine, the combination with a revoluble platen, feed-rolls to run thereon, and a carriage for said platen, of a rearwardly movable frame at the introductory side of the platen, and a set of carbon-blades or holders upon said frame between which plies of work-web are threaded,

said frame being stationary during all the letter-feeding and line-feeding movements of the carbons and work-web, and being shiftable rearwardly to clear the carbons from the platen, said carbon-blades or holders being detachable as a unit from said frame, together with the carbons and work-web, preparatory to the substitution of a different unit with other carbons and work-web.

7. In a typewriting machine, the combination with a revoluble platen, feed-rolls to run thereon, and a carriage for said platen, of a rearwardly movable frame at the introductory side of the platen, and a set of carbon-blades or holders upon said frame between which plies of work-web are threaded, said frame being shiftable rearwardly to clear the carbons from the platen, and said frame having a shelf or bar over which the plies of work-web hang in rear of the frame.

8. A typewriting machine having a line-feeding platen and a carriage therefor, a frame or support at the introductory side of the platen, the letter-feeding and line-feeding movements of the platen being independent of said frame or support, the latter carrying by its rear end a composite loop of work-web and carbons while the forward end of the loop is line-spaced with the platen, means connected to said frame for shifting it rearwardly, to straighten out the loop and clear the carbons from the platen, and a bracket upon which said frame is mounted, said bracket forming an attachment for the typewriting machine.

9. A typewriting machine having a line-feeding platen and a carriage therefor, a frame or support at the introductory side of the platen, the letter-feeding and line-feeding movements of the platen being independent of said frame or support, the latter carrying by its rear end a composite loop of work-web and carbons while the forward end of the loop is line-spaced with the platen, means connected to said frame for shifting it rearwardly, to straighten out the loop and clear the carbons from the platen, and a bracket upon which said frame is mounted, said bracket forming an attachment for the typewriting machine, and including arms which are removably secured to the bottom of the typewriting machine by means of its rubber feet.

10. A typewriting machine having a line-feeding platen and a carriage therefor, a frame or support at the introductory side of the platen, the letter-feeding and line-feeding movements of the platen being independent of said frame or support, the latter carrying by its rear end a composite loop of work-web and carbons while the forward end of the loop is line-spaced with the platen, means connected to said frame for shifting it rearwardly, to straighten out the

loop and clear the carbons from the platen, and a bracket forming an attachment for the typewriting machine, said frame pivoted to said bracket to swing backwardly and forwardly thereon.

11. A typewriting machine having a line-feeding platen and a carriage therefor, a frame or support at the introductory side of the platen, the letter-feeding and line-feeding movements of the platen being independent of said frame or support, the latter carrying by its rear end a composite loop of work-web and carbons while the forward end of the loop is line-spaced with the platen, means connected to said frame for shifting it rearwardly, to straighten out the loop and clear the carbons from the platen, and a bracket forming an attachment for the typewriting machine, said frame having arms and a cross-bar connecting them at their upper ends, and also having a rock-shaft to which the arms are fixed at their lower ends, and said rock-shaft journaled in said bracket.

12. A typewriting machine having a platen and a carriage, a bracket removably attached to the framework of the machine, a carbon-holder mounted on said bracket in rear of the platen and stationary during the platen movements, and a handle mounted upon said bracket and connected to said carbon-holder to shift the same rearwardly.

13. A typewriting machine having a platen and a carriage, a carbon-holder in rear of the platen and stationary during the platen movements, and a handle connected to said carbon-holder to shift the same rearwardly, means being operated by said handle for locking the carbon-holder temporarily in its rear position.

14. A typewriting machine having a platen and a carriage, a carbon-holder in rear of the platen and stationary during the platen movements, a lever and a link connecting said lever to said carbon-holder and co-operating with the lever to form a toggle locking the carbon-holder in its rear position.

15. A typewriting machine having a platen and a carriage, a carbon-holder in rear of the platen and stationary during the platen movements, a lever, a link connecting said lever to said carbon-holder and co-operating with the lever to form a toggle locking the carbon-holder in its rear position, and stops limiting the forward and backward movements of said lever.

16. In a typewriting machine, the combination of a rotatable platen, a letter-feeding carriage therefor, a support at the introductory side of the platen for supporting the rear end of a composite loop of multiple-ply work-web and carbons, the front end of the loop being connected with the platen, said loop-support being stationary during

the travel of the carriage and being movable rearwardly of the web to straighten out the loop, and means locking said loop-support against movement either forwardly or backwardly when in its rear position.

17. The combination with a typewriter platen, of means for holding a loop of composite web by its rear end while its forward end swings edgewise and feeds forwardly

10 around the platen, means for moving the loop backwardly to straighten it out and to pull the composite web back from the platen, and means for pulling forward the work-web relatively to the straightened-out carbons.

15 18. A detachable set for a typewriting machine having a traveling platen-carriage, including a bracket attachable to the framework of the machine, a loop-forming and straightening frame mounted upon said bracket at the introductory side of the platen and movable forwardly and rearwardly, but stationary with respect to the typewriter carriage, and a detachable work-supporting device mountable upon the platen-carriage of the typewriter at the delivery side of the platen and provided with gaging means for the leading edge of the web.

20 19. A detachable set for a typewriting machine having a traveling platen-carriage, including a bracket attachable to the framework of the machine, a loop-forming and straightening frame mounted upon said bracket at the introductory side of the platen and movable forwardly and rearwardly, but stationary with respect to the typewriter carriage, a detachable work-supporting device mountable upon the platen-carriage of the typewriter at the delivery side of the platen and provided with gaging means for the leading edge of the web, and a set of carbon-holding blades mounted upon said frame and detachable therefrom.

25 20. A detachable set for a typewriting machine having a traveling platen-carriage, including a bracket attachable to the framework of the machine, a loop-forming and straightening frame mounted upon said bracket at the introductory side of the platen and movable forwardly and rearwardly, but stationary with respect to the typewriter carriage, a detachable work-supporting device mountable upon the platen-carriage of the typewriter at the delivery side of the platen and provided with gaging means for the leading edge of the web, and side gages for the composite web attachable to the paper-shelf of the typewriting machine, said side gages having fingers to overlie the webs.

30 21. A detachable set for a typewriting machine, comprising a bracket attachable to the framework of the machine, a loop-forming and straightening frame mounted upon said bracket at the introductory side of the

35 platen and movable forwardly and rearwardly, a detachable work-supporting device mountable upon the platen-frame of the typewriter at the delivery side of the platen, and means upon said bracket for moving the frame rearwardly and forwardly.

40 22. In a typewriting machine, the combination of a rotatable platen, a letter-feeding carriage therefor, a support at the introductory side of the platen for supporting the rear end of a composite loop of multiply work-web and carbons, the front end of the loop being connected with the platen, said loop-support being stationary during the travel of the carriage and being movable rearwardly of the web to straighten out the loop, and means for locating the carriage with the portion of web thereon in line with the portion of web upon said support.

45 23. A detachable set for a typewriting machine having a platen-carriage, including a bracket attachable to the framework of the machine, a loop-forming and straightening frame mounted upon said bracket at the introductory side of the platen and movable forwardly and rearwardly, but stationary with respect to the typewriter carriage, a detachable work-supporting device mountable upon the platen-carriage of the typewriter at the delivery side of the platen and provided with gaging means for the leading edge of the web, and a web-severing knife upon said work-supporting device.

50 24. A detachable set for a typewriting machine, comprising a bracket attachable to the framework of the machine, a loop-forming and straightening frame mounted upon said bracket at the introductory side of the platen and movable forwardly and rearwardly, a detachable work-supporting device mountable upon the platen-frame of the typewriter at the delivery side of the platen and provided with gaging means for the leading edge of the web, said work-supporting device having upstanding bars at its ends, and a web-severing knife adjustable up and down on said bars for different lengths of printed forms.

55 25. A detachable set for a typewriting machine, comprising a bracket attachable to the framework of the machine, a loop-forming and straightening frame mounted upon said bracket at the introductory side of the platen and movable forwardly and rearwardly, a detachable work-supporting device mountable upon the platen-frame of the typewriter at the delivery side of the platen and provided with gaging means for the leading edge of the web, said work-supporting device having upstanding bars at its ends, and a web-severing knife adjustable up and down on said bars for different lengths of printed forms, a carbon-blade holder being detachably mounted on said frame and detachable therefrom, together

- with the composite web, for substitution of another carbon carrier and composite web.
26. In a typewriting machine having a rotatable platen and a letter-feeding carriage therefor, the combination with a support or holder to which the rear ends of carbons are attached, said support mounted at the introductory side of the platen for supporting the rear end of a loop or slack of multiple-ply work-web interleaved with the carbons, the front end of the loop being connected to the platen, and said loop-support being stationary during the travel of the carriage, of means to move said loop-support backwardly to straighten or lengthen out the loop and pull the composite web backwardly to clear the carbons from the typewriting mechanism, while the leading portion of the work-web remains upon the platen preparatory to advancing the web independently of the carbons, a gage for the leading end of the web to determine the extent of independent advance thereof, said loop-support being movable forwardly to make a new loop, and a second gage for the leading end of the web to determine the extent of advance of the composite web around the platen to bring the first typing line of the new form to the printing point, said gages independently adjustable relatively to the printing line of the platen.
27. In a typewriting machine, the combination of a rotatable platen, a letter-feeding carriage therefor, and a support at the introductory side of the platen for supporting the rear end of a composite loop of multiple-ply work-web and carbons, the front end of the loop being connected with the platen, said loop-support being stationary during the travel of the carriage and being movable rearwardly of the web to straighten out the loop, said loop-support having carbon-blades, and web-slitting knives being provided upon said carbon-blades.
28. In a typewriting machine, the combination with a revoluble platen, feed-rolls to run thereon, and a carriage for said platen, of a rearwardly-movable frame at the introductory side of the platen, a set of carbon-blades or holders upon said frame between which plies of work-web are threaded, said frame being stationary during all the letter-feeding and line-feeding movements of the carbons and work-web, and being shiftable rearwardly to clear the carbons from the platen, and means to limit the rearward movement of said frame, said frame having a cross-bar, and said carbon-blades being mounted upon a plate, and screws or hexives detachably holding said plate upon said cross-bar.
29. In a typewriting machine, the combination of a rotatable platen, a letter-feeding carriage therefor, and a support at the introductory side of the platen for supporting the rear end of a composite loop of multiple-ply work-web and carbons, the front end of the loop being connected with the platen, said loop-support being stationary during the travel of the carriage and being movable rearwardly of the web to straighten out the loop, said loop-support having carbon-blades, and loops of carbons upon said blades, each carbon-loop having carbon on only its front portion.
30. In a typewriting machine, the combination of a rotatable platen, a letter-feeding carriage therefor, and a support at the introductory side of the platen for supporting the rear end of a composite loop of multiple-ply work-web and carbons, the front end of the loop being connected with the platen, said loop-support being stationary during the travel of the carriage and being movable rearwardly of the web to straighten out the loop, said loop-support having carbon-blades, each of said blades having a lengthwise reversible carbon-loop having carbon on its front and rear portions and an extensive intervening blank portion.
31. In a typewriting machine, the combination of a rotatable platen, a carriage, a rear loop-supporter to which the rear ends of carbons are attached, said supporter stationary with respect to the carriage travel but movable backwardly for withdrawing the looped carbons and interleaved plies of a typed work-web form preparatory to advancing the typed web independently of the carbons, a gage at the delivery side of the platen to measure the extent of such independent advance of the typed web relatively to the stationary carbons, a second gage to measure the extent of subsequent advance of the typed web to a web-severing position and the composite web and carbons to a new typing position, and a blade positioned above the first gage for severing the typed web-form when set to the second gage.
32. In a typewriting machine, the combination of a rotatable platen, a carriage, a rear loop-supporter to which the rear ends of carbons are attached, said supporter stationary with respect to the carriage travel but movable backwardly for withdrawing the looped carbons and interleaved plies of a typed work-web form preparatory to advancing the web independently of the carbons, a gage at the delivery side of the platen to measure the extent of such independent advance of the typed web relatively to the stationary carbons, a second gage to measure the extent of subsequent advance of the typed web to a web-severing position and the composite web and carbons to a new typing position, and a blade positioned over the first gage for severing the typed web-form when set to the second gage, said blade adjustable to and from said second gage to accommodate various lengths of forms.

33. The combination in a typewriting machine having a web-feeding platen, of means for holding a loop of composite web at the rear of the platen while the forward end of the web feeds around the platen for typing, means for straightening out the loop and pulling the composite typed web rearwardly of the platen to strip the carbons, a carbon-locating gage for engaging the end of the

typed web to relocate the carbons within 10 the web, and a gage for subsequently engaging the same end of the web to locate the typed web at web-severing and typing positions, said carbon-locating gage being a little more than a form's length nearer to the 15 platen than is the web-severing gage.

BURNHAM C. STICKNEY.
